(57) **CLAIM**

The ornamental design for an adjustable glasses, as shown and described.

DESCRIPTION

FIG. 1 is an isometric view of an adjustable glasses showing our new design;

FIG. 2 is a front elevation view thereof;

FIG. 3 is a rear elevation view thereof;

FIG. 4 is a side view thereof;

FIG. 5 is a top view thereof;

FIG. 6 is a bottom view thereof; and,

FIG. 7 is a perspective view thereof.

The broken lines shown represent unclaimed subject matter and form no part of the claimed design.
